UNITED STATES PATENT OFFICE.

HENRY C. DIERS, OF MARSHFIELD, OREGON, ASSIGNOR OF ONE-FOURTH TO GEORGE A. MARTIN, ONE-FOURTH TO EARL W. MCINTURFF, AND ONE-FOURTH TO WILLIAM T. STOLL, ALL OF MARSHFIELD, OREGON.

APPARATUS FOR MAKING ARTIFICIAL FUEL.

Application filed April 2, 1921. Serial No. 458,138.

To all whom it may concern:

Be it known that I, HENRY C. DIERS, a citizen of the United States, residing at Marshfield, in the county of Coos and State 5 of Oregon, have invented new and useful Improvements in Apparatus for Making Artificial Fuel, of which the following is a specification.

This invention relates to apparatus for 10 the manufacture of artificial fuel and has for its object the provision of an apparatus for converting waste material such as lignite or other non-coking coal and waste wood of all kinds into an artificial coal of any desired grade which will have all the advantages with practically none of the disadvantages of natural coal.

In a separate application Serial No. 452, 20 294, filed March 14, 1921, I have set forth my process which might be carried out with a different apparatus but the present invention contemplates the provision of a specific apparatus for carrying out the process mentioned in the companion application. The 25 process referred to involves the carbonizing of lignite or other non-coking coal and of wood by distilling separately in suitable retorts to drive off the tars and other volatile matter and also the moisture. The carbonized materials are then pulverized and mixed together and then have added thereto a certain amount of the tar previously removed by the distillation referred to, after 30 which the mass is mixed and deposited onto a hard bed upon which the mass is rolled by means of a species of steam roller having heated rollers whereby the mass will be greatly compressed so as to make a compact homogeneous mass.

40 An important and more specific object of the present invention is the provision of a comparatively simple apparatus for very efficiently carrying out the above described process in an expeditious manner.

45 With the above and other objects and advantages in view, the invention consists in the details of construction, to be hereinafter more fully described and claimed, and illus-

trated in the accompanying drawings; in which:—

50 Figure 1 is a diagrammatic side elevation of my complete device.

Figure 2 is a longitudinal sectional view through a portion thereof.

55 Figure 3 is a longitudinal sectional view through the remainder thereof, and the remaining figures are detail views of the rolling bed.

Referring more particularly to the drawings the numeral 10 designates a grinder of 60 conventional pattern, which is provided for the purpose of reducing the coal, wood or other carbonaceous material to any suitable size desired. This grinder discharges into the lower end of an elevator 11 which includes an upwardly moving conveyor 12 65 driven by any suitable means, not shown. At its upper end this elevator 11 discharges into a bin 13 below the lower end of which is disposed a receiving hopper 14 which 70 leads at its bottom into an upwardly inclined casing 15 within which is located a screw conveyor 16 driven by a beveled gear 17 with which meshes a bevel gear 18 on a shaft 19 driven by any suitable means. 75

The upper end of the casing 15 discharges into the upper end of a retort structure designated broadly by the numeral 20. This retort device comprises an outer casing 21 provided near its top with a smoke pipe 22 leading to any suitable stack, not shown, and communicating at its lower end with a suitable fire-box 23 beneath which is a conventional ash pit 24. The retort proper comprises a casing 25 which has its 80 upper end reduced and leading into the upper end of the casing 15 and which has its lower end extending through the bottom part of the outer portion 21 of the retort and terminating in a downwardly inclined 85 chute 26. A suitable sliding door 27 is provided for controlling the outlet at the lower end of the discharge chute 26. Leading from the upper portion of the inner casing 25 is a take-off pipe 28 which leads into a 90 hydraulic main 29 which conducts the dis-

tillate to any suitable reservoir. A pipe 30 leads from this reservoir into the fire-box 23 for conducting volatile gases from the hydraulic main into the furnace whereby to 5 provide fuel for the necessary heat to effect distillation of the material within the retort casing 25. When the retort casing 25 has been filled with coal, wood or other carbonaceous matter it is apparent that the application of heat thereto by means of the 10 furnace will result in distillation of the material in the usual manner, the distillates passing out through the take-off pipe 28 into the main 29 and the remainder of the material being carbonized and remaining in 15 the retort.

Located beneath the discharge end of the chute 26 is a hopper 31 into the upper portion of which leads a pipe 32 having a valve 33 and provided with a discharge nozzle 34 for the purpose of discharging steam onto the carbonized material when the latter is allowed to pass out of the chute 26. The purpose of the steam is to cool off the 20 carbonized material. Leading from the hopper 31 is a horizontally disposed casing 35 within which is located a screw conveyor 36 driven by any suitable means. This screw conveyor discharges into the top 25 of a pulverizing device of conventional pattern indicated by the numeral 37.

The pulverizing device 37 discharges into the lower end of an upwardly inclined casing 38 within which is an elevator 39 which 30 discharges into the rear end of a conventional mixing device indicated at 40. Disposed above the casing 38 and the mixer 40 is a reservoir tank 41 which contains coal tar and wood tar or a suitable pitch and 35 leading from the tank 41 is a valve controlled pipe 42 which discharges into the upper portion of the casing 38 and consequently into the end of the mixer 40 together with the material dropped into the 40 mixer by means of the elevator 39. The numeral 43 designates the discharge end of the mixer 40 and it is intended that a suitable car 44 be capable of disposition beneath the discharge end of the mixer to 45 catch the mixed material issuing therefrom. This car may be run on tracks if preferred but at any rate it is adapted to conduct the mixed material to a hard bed, designated broadly by the numeral 45.

50 The bed 45 comprises a comparatively smooth surface the bed proper of suitable length, width and material beneath which is disposed heating means shown as a serpentine coil 46 through which steam may be 55 circulated for effecting heating of the plate. The mixed material deposited in the car 44 is transported to the bed 45 and is spread thereon. The thickness of the layer of material thus spread onto the bed 45 is a mat-

ter of choice and depends to a great extent upon the consistency of the mixture.

In order to compress and drive off volatile gases from the mixture, I provide a roller device which is indicated by the numeral 47, the only distinctive feature being that this roller device includes rollers 48 which are steam heated by means of steam passing through hollow axles 49 thereof.

I also preferably make use of an upwardly inclined conveyor 50 at the end of the rolling bed most remote from the mixer 40, this elevator 50 discharging into a loading device 51 from which the material when finished may be loaded into cars, wagons or the like.

In the operation of the device it will be seen that the material ground in the grinder 10 will be deposited in the retort casing 25 where it will be distilled so as to remove the moisture, the gases, and also the volatile oils, tars, pitch and the like. The resultant carbonized material remaining within the retort is passed into the hopper 31 and into the pulverizer 37 from whence it will pass into the mixer 40 at which point the certain percentage of coal tar, wood tar, and pitch is added.

The material discharged from the mixer 40 is spread onto the bed 45 and rolled by means of the steam roller device 47 until it is hard and compact. A second layer of the mixture is then spread over the layer thus rolled and the operation is repeated until the mass upon the bed is of the desired thickness. After this material has been allowed to cool it is broken into pieces of any desired size depending upon the use to which the fuel is to be put and then 100 pieces are conveyed by means of the conveyor 15 to the loading device 51.

In the actual carrying out of my process I have found that the above described method produces a very efficient artificial coal which has all of the good qualities of regular anthracite coal or coke. It is also to be observed that different proportions of coal, wood and the binding material may be varied so as to produce a product of varying grades.

From the foregoing description and a study of the drawings, it will be apparent that I have thus provided a comparatively simple and therefore inexpensive apparatus by means of which my process may be carried out efficiently and rapidly and without any waste in any way.

While I have shown and described the preferred embodiment of the invention, it is of course to be readily understood that I reserve the right to make such changes in the form, construction and arrangement of parts as will not depart from the spirit of

the invention or the scope of the subjoined claim.

Having described the invention what is claimed is:—

- 5 An apparatus for making artificial fuel comprising a destructive distillation retort, means for applying steam to the heated solid matter being discharged from the re-

tort, a heated hard bed to receive the steam-treated solid matter, a rolling device having 10 heated rolls and operating upon such heated bed, all arranged in combination substantially as described.

In testimony whereof I affix my signature.

HENRY C. DIERS.
